UNITED STATES PATENT OFFICE.

CONSTANTINOS PANFILIS, OF PITTSBURGH, PENNSYLVANIA.

WINDLASS MECHANISM.

Application filed December 28, 1926. Serial No. 157,542.

My invention relates to windlass mechanisms and has for its object the provision of a cord, rope or cable operated device for hoisting or lowering a load, winding or unwinding a curtain, or for hauling a load wherein it is necessary or desirable to hold the load or curtain suspended at any intervening point between the limits of its travel.

It is the further object of my invention to provide economic and efficient means by which a heavy load can be easily hoisted or hauled, or a heavy curtain can be easily wound or unwound by the application of comparatively small amount of power.

It is the further object of my invention to provide sure and efficient means which will automatically stop and hold the load suspended at practically any desired point between the limits of its travel, and to again automatically release the load and to permit the change of its position, when such change is desired.

It is the further object of my invention to provide a windlass mechanism which shall be of universal application and which shall be cheap to manufacture, simple to operate, and efficient in use.

My invention further comprehends the provision and arrangement of parts and other features of novelty hereinafter more fully described, reference being had to the accompanying drawings which form a part of this application, and in which:

Fig. 1 shows my invention applied to a window blind;

Fig. 2 shows a cross sectional view of the winding mechanism, the adjustable pole on which the window blind winds and unwinds, and the manner of attaching the winding mechanism to the thimble-end of the pole;

Fig. 3 is a cross sectional view of the other end of the pole and the manner in which it is supported on the bracket;

Fig. 4 is a section taken on line 4-4 of Fig. 2, looking in the direction of the arrows;

Fig. 5 is a cross sectional view taken on line 5-5 of Fig. 2, looking in the direction of the arrows and showing the automatic means for stopping the lifting or lowering, or the winding or unwinding operations and holding the load or curtain at a certain place.

Fig. 6 shows the exterior of the hollow bracket which houses the spool;

Fig. 7 shows a modified construction of

the connecting means between the windlass mechanism and the curtain pole;

Fig. 8 is a cross sectional view taken on line 8-8 of Fig. 7, looking in the direction of the arrows;

Fig. 9 is a cross sectional view of a modified form of my invention adaptable for use in the hoisting, lowering, or hauling of compact or bulky loads;

Fig. 10 is a cross sectional view taken on line 10-10 of Fig. 9, looking in the direction of the arrows;

Referring now more particularly to the drawings wherein corresponding numerals are used to designate similar parts in the different views herein above briefly described:

Numeral 1 designates the jambs of a window on which brackets 2 and 3 are securely fastened in the usual manner for the purpose of supporting the ends of the rod 4 on which the curtain, or blind, 5 is adapted to wind or unwind by turning the rod counter-clockwise or clockwise, as the case may be.

The ends of the pole 4 are in the form elongations 6. These ends are of smaller diameter than the main body of the pole and are adapted to receive the thimbles 7 which fit slidably over the ends of the pole and are held against relative rotation therewith either by friction or by the use of a set screw of any ordinary type.

The thimbles 7 by slidably fitting or telescoping over the reduced ends of the pole, serve two main purposes; to wit: firstly, they adjust the length of the pole to fit a window of practically any width, and secondly, by being provided with necessary parts and construction, afford means for attaching thereto my windlass mechanism by the operation of which the curtain, or blind, may be raised or lowered.

One of the brackets, in this instance bracket 2, and outer end of one of the thimbles, in this instance the thimble illustrated at Fig. 3, may be of any ordinary construction which will allow the end of the thimble to rotate freely and with the least possible friction within the bracket. Such a construction and co-operation of parts is generally shown at the left hand side of Fig. 3.

Referring now to brackets 3, and the structures illustrated at Figs. 2 and 4 to 6 inclusive, bracket 3 is in the form of a hollow shell having a comparatively large circular

chamber 8, and elongated ears 9 formed of flat inner surfaces adapted to fit on to a window jamb and to be secured thereto by screws passing through the apertures 10. The bracket 3 is further provided with axial and longitudinal slots 18 and 19 respectively. And, it is also provided with slots 20 either one of which is adapted to receive the ball 21. In the slot 19 is mounted a roller 22 the outer rim of which is in alinement with the axis of the aperture 18.

Numeral 11 designates a circular drum or spool having a deep recess 12 into the bottom of which leads aperture 13. The drum, or spool 11 is further provided with projections 14 and 15 at its outer and inner sides respectively. The inner projection 15 is provided with indentations 16. Passing centrally through the core of the drum, or spool, is a circular boring 17.

On the periphery of the drum 11 there is formed a notch 27. This notch is so cut that one side wall thereof is substantially perpendicular to the axis of the drum and the other side wall is disposed at an angle to the said axis. The notch is cut at such a place on the drum as to bring it in contact with the apertures 20.

Both thimbles are provided with flanges 23 for the purpose of confining the edges of the curtain within the ends of the pole.

The outer end of the thimble shown at Fig. 2 is provided with a long projection 24 the end of which is screw-threaded to receive the nut 25. On either side of the long projection 24 are lugs 26.

Around the depression 12, which is of substantial width and depth, there is wound a cord 28.

Now, to assemble and put into use and operation my device, when used in connection with the raising and lowering of a curtain, it is only necessary to first fix the brackets 2 and 3 in place. Bracket 3, having flanges 29 and 30, and apertures 18 and 20 at both ends, renders it reversible and adaptable to practically any location or situation.

The brackets being in place, the thimbles are slipped on the curtain-pole and the pole, with the curtain on it, is mounted on the brackets, care being taken that the thimble of the structure shown at Fig. 2 should be mounted in bracket 3. Then one end of the cord 28 is pulled through aperture 13 until a knot, at the other end of the cord stops up against the outer opening of the aperture. The cord is then wound around the axle of recess 12, and the other end of the cord is passed through aperture 19 over the roller 22 and down through aperture 18 and alongside the window jamb as shown at 31, Fig. 1. This being done, the end of the thimble in bracket 3 is lifted up and the drum, or spool, 11 is slipped in the opening 8 of the bracket, projection 24 passing through the central

bore of the spool, and lugs 26 fitting in depressions 16. The nut 25 is then threaded in place, and the ball 21 is dropped in the hole 20.

Now, to raise the curtain, it is only necessary to pull the cord-end 31 downward, causing the ball 21 to play up and down in slot 20, and the curtain to be rolled up on the pole 4. When it is desired to stop the curtain at any point, the rope is held fast and then pulled up and down slowly, until the ball lodges in notch 27 as shown at Fig. 5. This locks the drum against rotation and the curtain is held securely at the desired place. To unroll, or lower the curtain, the rope is jerked gently, thus dislodging the ball from the notch and the curtain is allowed to roll down by force of gravity, and again, by holding up on the rope the ball relodges in the notch and the movement of the curtain stops.

The structure shown at Fig. 7, is similar to that at Fig. 2, with the exception that the thimble is formed with a single square projection 32 at the center of its outer surface. This projection 32, has a threaded bore and fits in a recess 33 of the drum, and its threaded bore comes in alinement with the axial bore of the drum. A threaded bolt 34 passes through the axial bore of the drum and threads into the threaded recess of the projection 32, thus holding the drum and thimble together. In this structure I also provide detachable side plates 35 and 36 for the bracket in this structure. The rest of the structure is substantially the same as that shown at Fig. 7.

Numeral 37, at Fig. 8, designates a pin, which, passing through across the top of the opening 20, serves as a keeper to prevent the ball 21 from jumping out of its recess.

When the diameter of the drum, or spool, is comparatively large, it may be provided with any desirable number of notches. This will enable it to stop at closer intervals because it will afford more places at which the ball can lock it in place.

The form of the device shown at Figs. 9 and 10 is adapted to lift or lower, or haul compact weights in bulk. Here, instead of the bracket I use a casing 38 which is provided with detachable socket pieces 39 on which is mounted a drum 40. This drum is provided with two wide and deep recesses 41 and 42. It will be noted that one of these recesses is deeper than the other, thus affording a differential in the diameters of the two winding compartments of the drum. That is, the diameter of one compartment is larger than the other. On each of these compartments is wound a rope one counter-wise to the other, so that winding the one unwinds the other, and vice versa. At the top of the casing 38 is hinged a hoop or bale 42 at center of which is swivelly connected a loop or

ring 43 which is held stationary by means indicated by numeral 44, which may be either a hook, cable or rope.

When this form of the device is secured in place, the load to be lifted, or lowered, or hauled may be attached to the end of the rope wound on either of the compartments of the drum. As to which rope to choose depends upon the weight of the load and the speed with which it is desired to move it. The operation is the same as that described in connection with the curtain, and the means of stopping is the same, ball and notch, as shown at Fig. 10.

It is thus apparent from the foregoing description and illustrations in the accompanying drawings that I have invented a new and useful improvement in windlass mechanisms, and as is badly needed for the raising and lowering of curtains and loads. My invention is also simple in construction and operation, durable and efficient in service, because it eliminates the use of springs. The same can also be cheaply manufactured and sold at a reasonable price.

It is also obvious that while I have herein described what I have found to be very practical embodiment and application of my invention, the specific details of construction and configuration of parts may be modified, and the invention itself may be applied to other uses without departing from the spirit and scope thereof as defined in the appended claims.

Having now set forth my invention in the foregoing specification and having further illustrated the same in the accompanying drawings, what I claim as my own and desire to secure by Letters Patent of the United

States is:

1. In a windlass mechanism for lifting, lowering or hauling a load, the combination

of a stationary casing, a drum supported in the casing, wide recesses on the drum, said recesses being of different depths and separated into compartments by flanges; a rope wound on one of the recesses for causing the drum to rotate and a winding means counter to the said rope on another of the recesses for moving a load relative to the drum when said drum is rotating; with a notch on one of the flanges of the drum, a slot in the casing, said notch and slot being adapted to come in alinement with each other forming a recess between the casing and the drum, and a ball in the slot which, when the drum rotates slowly, lodges in the notch thereby locking the drum against further rotation relative to the casing.

2. A device for hoisting, lowering or hauling a load, comprising a stationary hollow casing, said casing having a slot disposed vertically thereof and a slot disposed horizontally thereof; the vertical slot extending the full length of the casing and the horizontal slot extending from one side into the hollow of the casing; a wheel rotatably mounted in the horizontal slot, the rim of said wheel being grooved and the axis of the vertical slot forming a tangent to the groove of the wheel; a drum mounted in the casing, a rope passing through the vertical slot and over the wheel in the horizontal slot; a portion of said rope being permitted to hang outside of the casing and the other portion being wound on a portion of the drum; flexible means wound on another portion of the drum and counterwise to the said rope; and spherical locking means co-operating with the drum and the casing for automatically stopping and releasing the drum.

In testimony whereof, I have hereunto set my hand this 28th day of December, 1926.

CONSTANTINOS PANFILIS.
